UNITED STATES PATENT OFFICE

160,144

DISPLAY RACK

Nathan J. Brown, Barrington, Ill.

Application December 10, 1949, Serial No. 6,548

Term of patent 14 years

(Cl. D80—10)

To all whom it may concern:

Be it known that I, Nathan J. Brown, a citizen of the United States, residing at Barrington, in the county of Lake and State of Illinois, have invented a new, original, and ornamental Design for a Display Rack, of which the following is a specification, reference being had to the accompanying drawing, forming a part thereof.

Fig. 1 is a perspective view of the display rack embodying the new design; and

Fig. 2 is a side view.

I claim:

The ornamental design for a display rack, as shown.

NATHAN J. BROWN.
